WATER-VAPOR REFRIGERATING
APPARATUS

George H. Woodard, Phillipsburg, N. J., and John Kirgan, Easton, Pa., assignors to Ingersoll-Rand Company, Jersey City, N. J., a corporation of New Jersey

Application September 26, 1934, Serial No. 745,536

16 Claims. (Cl. 62—152)

This invention relates to water-vapor refrigerating apparatus, and particularly to apparatus of that type with steam jet evacuator members.

An object of the invention is to provide refrigerating apparatus which can be assembled with one part above another, the parts being preferably in coaxial alignment, thus enabling space to be saved horizontally wherever ample vertical room is available.

10 Another object is to provide refrigerating apparatus which, when set up, is braced and made strong and rigid by the disposition and connection of the various parts.

15 A further object is to provide in refrigerating apparatus of this kind an evaporator of special design, adapted for full or part loads and constructed so that it can easily be built into a vertical arrangement, as set forth.

20 An additional object is to provide vapor refrigerating apparatus having an evaporator containing multiple chambers, a condenser supported above the evaporator and a plurality of steam jet evacuator members extending from the evaporator to the condenser and buttressing the latter.

25 A further object is to provide refrigerating apparatus having an evaporator vessel and condenser vessel in coaxial vertical alignment, and having evacuator members conveying vapor from the evaporator to the condenser, the members being symmetrically arranged around the peripheries of the evaporator and condenser and being connected to each to act as braces for the uppermost vessel.

30 The foregoing and other objects and advantages of the invention are fully disclosed in the ensuing description, taken with the accompanying drawing, which shows several embodiments of the invention. We of course, reserve the right to make changes not illustrated herein, but embraced within the principle of the invention, as the claims define the same.

35 On the drawing, Figure 1 shows a side elevation of one form of the invention, partly in section.

Figure 2 shows a horizontal cross section 45 through the evaporator of another form, and

Figure 3 shows a vertical section substantially on line 3—3 through the evaporator of Figure 2.

On the drawing the same numerals identify the same parts throughout.

50 The preferred construction embodies an evaporator 1 above which is a barometric condenser 2. The evaporator 1 receives water or some other liquid refrigerant, which is partly converted into vapor therein to cool the main body of the wa-55 ter, and this vapor is delivered to the condenser

2 by means of evacuator members in the form of steam jet boosters indicated generally by the numeral 3. These boosters connect the top of the evaporator 1 with the condenser 2, and between the bottom of the condenser and the top of the evaporator 1 is an upright column 4. Preferably the evaporator 1, condenser 2 and column 4 will be in vertical coaxial alignment. The weight of the condenser rests upon the column 4 and the casings of the boosters, being symmetrically arranged 10 around the peripheries of the evaporator and condenser, brace and stiffen the condenser in all directions and make the entire construction rigid. The evaporator 1 is mounted on suitable supports, indicated at 5, having feet 6 fastened 15 to or imbedded in the supports 5. These feet may be of any suitable shape or material and are shown as consisting of U-shaped members of iron or steel resting upon the supports 5 and being shouldered so as to receive the lower end of the 20 evaporator 1.

The evaporator has an inlet 7 through which water is admitted, and this water, after being cooled, is discharged through an outlet 8. Cooling water is admitted to the condenser through 25 an inlet 9 and is discharged therefrom through a pipe 10 into a well 11. The pipe 10 has a joint at its upper end to enable it to make connection with the column 4, which is hollow and may serve as a tail pipe for condenser 2. Preferably this column is formed of a section of pipe, joined at its flanged upper end to a flanged outlet neck 12 at the bottom of the condenser 2 and having its flanged lower end engaging a similar flanged neck 13 on the top of the evaporator 1. 35 Any suitable means can be employed to secure the column to these two necks. The neck 13, or the column 4 at any point below its junction with the pipe 10, is closed so that no communication 40 between the evaporator and the condenser by way of the column 4 is permitted. This column is thus forced to act as above stated to support the condenser, and serves also to enable the liquid from the vapor and steam condenser therein to drain down to the well 11. The evaporator 45 and condenser are thus located directly above this well.

In action, the water entering the evaporator 1 through the inlet 7 is at such a temperature that part of it is at once converted into vapor in the 50 evaporator, because the steam jets within the evacuator members 3 create a sufficiently high vacuum to cause vaporization in the evaporator 1 in a manner well understood. Steam is supplied to the members 3 through inlet pipes 14 55

branching from a common supply pipe 15 connected to the heads 16 of the evacuators 3, these heads each containing one or more nozzles to form jets. The heads of the evacuators communicate with the inside of the evaporator 1 near the top, and the steam jets draw water vapor out of the evaporator 1 by aspiration, and discharge it upwards in the evacuators 3. Just above the heads 16 are the elongated tubular discharge casings 17 of the evacuators, and at the upper ends of the casings 17, bent or goose neck sections 18 put the evacuators into communication with the interior of the condenser. The steam and vapor are liquefied in the condenser 2 and flow downward through the column or tail pipe 4 and pipe 10 into the well 11. Some of the water in the well 11 may be piped into the evaporator 1 to take the place of the water which is vaporized.

20 In practice the water coming in by way of the inlet 7, after being cooled in the evaporator and discharged through the outlet 8, is led off to a cooling coil or spraying chamber. After absorbing heat and thus producing a refrigerating effect, it is returned to the inlet 7 to be cooled again.

To obtain vacuum in the condenser 2, a pipe 19 is connected with the top thereof and leads down to suitable means, such as a two-stage 30 evacuator with inter-condenser 20. This inter-condenser 20 will be cooled by water from the cooling water supply of the condenser conveyed to the inter-condenser 20 through a pipe 21. Connected to the inter-condenser are the steam 35 jet evacuators indicated at 20a and 20b. The effect of the former, 20a, is exerted through the pipe 19 to create the vacuum in the condenser 2 of the required degree. These evacuators are joined to the steam supply pipe 15 by a branch 40 pipe 22. Pipe 23 affords an outlet for condensate from the inter-condenser 20 leading down to the well 11. At 24 is another pipe to convey vapor and air from the other evacuator 20b and the inter-condenser down to the well 11. The well 45 11 has a weir 25 over which the water from the pipes 10 and 23 passes and the end of the pipe 24 is so situated that it receives the discharge from this weir to condense the vapor that issues therefrom. The well 11 has an outlet 26.

50 Figures 2 and 3 show the construction of the evaporator which is adapted to be built into an arrangement of this kind. The evaporator has transverse partitions 27 therein which intersect in the middle, dividing the evaporator into four 55 vertical chambers, each of which has an outlet neck 28 to which the head 16 of one of the ejectors 3 is attached. The water can be passed in through the inlet 7 at the bottom by way of a neck 29 which is enlarged at the upper end 30. 60 The partitions 27 terminate above the bottom of the evaporator, at the level where this enlargement begins. This enlargement is in line with the intersection of the transverse partitions and extends up into the four chambers 27. It 65 contains four wells 31, one in each chamber. These wells are formed by extensions 32 into the enlargement 30 of the partitions 27. The wells when the chambers are in operation, discharge water over their upper edges. However, if one 70 of the chambers is to be cut out for the time, the supply of steam is cut off to one of the evacuators 3. The condenser pressure is then free to act upon the interior of that particular chamber in the evaporator 1, forcing down the level of the 75 water to a point nearly as far as the chilled wa-

ter outlet 8, and in the well 31 thereof considerably below the upper end thereof. Hence, no more water can enter that chamber. Nevertheless, the bottom of that chamber is sealed off from the rest of the evaporator by the level of 5 the chilled water therein which is above the bottoms of the partitions 27 as shown in Figure 3. Hence, when the load drops and one or more of the chambers are to be rendered inoperative, the operator needs only to cut off the steam to 10 one or more of the evacuators, but no valves in the intake 7, or outlet 8, or the casings 17 are necessary. The evaporator 1 then continues to operate as before on the chambers that still continue in action. The partitions 27 of course extend from their lower ends quite to the top of the evaporator 1.

In this construction it will be seen that the invention can be very easily set up and it is made rigid and tight and firmly braced by the 20 ejector heads and casings between the evaporator 1 and condenser 2.

The construction in Figure 1 is shown with three evacuator members, hence the evaporator will have three chambers and the enlargement 30 25 will be divided into three wells. Figures 2 and 3 are modifications of the construction shown in Figure 1 wherein the evaporator is shown as containing four chambers and adapted for four ejectors. Of course, the number of evaporator 30 chambers and ejectors can be varied.

We claim:

1. Refrigerating apparatus comprising an evaporator, a condenser above the evaporator, and evacuator members connecting the evaporator to the condenser and bracing the latter.

2. Refrigerating apparatus comprising an evaporator, a column on the top of said evaporator, a condenser supported by the column, and evacuator members connecting the evaporator 40 to the condenser and bracing the latter, said column being hollow to serve as an outlet for the liquid contents of the condenser.

3. Refrigerating apparatus comprising an evaporator having a column extending upward 45 therefrom, a condenser resting upon the column, and a plurality of evacuator members extending from the evaporator to the condenser, said members bracing the condenser and stiffening said apparatus.

4. The combination of an evaporator, a condenser above the latter, steam jet evacuators connecting the evaporator to the condenser and buttressing the latter, a supply conduit extending up into the evaporator from the bottom and having an enlargement in the evaporator, and partitions extending inward from the wall of said evaporator and down from the top and intersecting within said enlargement to form chambers in the evaporator and supply wells in the enlargement, each chamber having one supply well therein, said chambers terminating above an outlet in the bottom of the evaporator.

5. Refrigerating apparatus comprising an evaporator, a column on the evaporator, a condenser supported on said column and steam evacuator members connecting the evaporator to the condenser and buttressing the same on the latter.

6. Refrigerating apparatus comprising an evaporator having vertical partitions therein intersecting at the middle of the evaporator to form chambers, and steam jet evacuators connected to the chambers of the evaporator.

7. The combination of an evaporator having 75

transverse partitions intersecting at the middle and extending downward from the top but terminating short of the bottom to form chambers therein, a member within the evaporator to admit fluid, said member being in line with the intersection of said partitions which are extended into same to form wells, one for each of said chambers, and evacuator connected to said chambers.

10. 8. The combination of an evaporator, a condenser above the same, means extending vertically in the evaporator dividing the same into a plurality of chambers, an upward extending evacuator connecting each of said chambers to the condenser, and supply means secured to the lower part of the evacuator, said supply means extending upward into the chambers to provide wells admitting a refrigerant thereto.

9. The combination of an evaporator, a condenser above the same, means extending vertically in the evaporator dividing the same into a plurality of chambers, an upward extending evacuator connecting each of said chambers to the condenser, and supply means secured to the lower part of the evacuator, said supply means extending upward into the chambers for admitting a refrigerant thereto and cooperating with the first-named means to form a well in each of said chambers.

30. 10. In refrigerating apparatus, vessels comprising an evaporator and a condenser in co-axial vertical alignment, and means conveying vapor from the evaporator to the condenser and acting to buttress the uppermost vessel.

35. 11. In refrigerating apparatus, vessels comprising an evaporator and a condenser in the same vertical plane, means conveying vapor from the evaporator to the condenser, and means between and co-axially aligned with the evaporator and the condenser whereby one vessel supports the other.

40. 12. In refrigerating apparatus, an evaporator, a condenser superposed on and co-axially aligned with the evaporator, and members for conveying vapor from the evaporator to the condenser, said members being symmetrically arranged around

the peripheries of the evaporator and condenser and being connected to each to act as buttress means for the condenser.

13. In refrigerating apparatus, an evaporator, a condenser co-axially aligned with the evaporator, means whereby the evaporator supports the condenser vertically thereabove and in fixed relative position therewith, and evacuator members conveying vapor from the evaporator to the condenser, said members being spaced equi-distantly around the peripheries of the evaporator and condenser and being connected to each to act as braces for the condenser and the said means.

14. In refrigerating apparatus, an evaporator, a condenser in the same vertical plane as the evaporator, means co-axially aligned with the evaporator and condenser and acting to support the condenser on the evaporator, said means also acting to convey condensate from the condenser, and a plurality of evacuator members conveying vapor from the evaporator to the condenser, the members being symmetrically arranged around the peripheries of the evaporator and condenser and being connected to each to prevent movement of the condenser transversely to the axis of said means.

15. In refrigerating apparatus, an evaporator having its axis in vertical position, means forming a plurality of chambers in the evaporator, means forming a well in each chamber for liquid refrigerant, and means forming an outlet from each chamber for vapor, the chambers, wells and outlets being in symmetrical arrangement and the axis of symmetry being coincident with the axis of said evaporator.

16. The combination of an evaporator, a condenser arranged to receive vapor from the evaporator, a hotwell arranged to receive the liquid contents of the condenser, a weir governing liquid overflow from the hotwell, and an evacuator for the condenser arranged to discharge vapors into the path of the liquid flowing over said weir.

45. GEORGE H. WOODARD.
JOHN KIRGAN.
